UNITED STATES PATENT OFFICE.

CESIDIO DEL PROPOSTO, OF NICOLAEFF, RUSSIA.

OPERATION OF SHIPS' PROPELLERS.

No. 832,622.

Specification of Letters Patent.

Patented Oct. 9, 1906.

Application filed November 27, 1903. Serial No. 182,893.

To all whom it may concern:

Be it known that I, CESIDIO DEL PROPOSTO, engineer, a subject of the King of Italy, residing at Nicolaieff, in the Empire of Russia, have invented certain new and useful Improvements in and Relating to the Operation of Ships' Propellers, of which the following is a specification.

The engines used for the operation of ships' propellers are generally adapted to be reversed and to be varied in speed in wide limits; but there are other engines which, on account of their mode of operation, are adapted to rotate in one direction only at different speeds (steam or gas turbines and the like) or which are adapted to rotate in one direction only and at a speed which is practically constant, (explosion and combustion motors for gas, alcohol, benzine, petrol, raw naphtha, and the like.)

This invention has for its object to allow of the application of the above-indicated engines or motors (which in ordinary cases are unsuitable for operating ships' propellers) for directly operating ships' propellers, while practically avoiding the losses of energy which would be caused by using a system of transmission between the said motors and the propeller-shaft.

The invention is also applicable in all cases where the engine, being adapted to be reversed and to be varied in speed, it is preferred to have it running at a constant speed and in one direction only.

The invention consists mainly in the interposition upon the propeller-shaft, suitably divided by clutches, of an electric dynamo and motor serving as intermediate transmission member between the engines and the propeller-shaft only when it is desired to vary the velocity of the propeller and reverse the direction of rotation, the engines driving the propeller-shaft directly when the vessel is running normally.

Referring to the annexed drawings, Figure 1 is a diagram of an installation according to the invention. Fig. 2 shows a modification.

According to my invention upon a prolongation of the propeller-shaft E is arranged, in addition to the engine A, Fig. 1, a dynamo B and an electric motor C, adapted to be supplied by the dynamo and of approximately the same power as this latter. The motor C is constantly connected to the shaft E by means of a fixed coupling-box M¹. A similar

coupling M¹ couples the dynamo B directly to the engine A. Between the dynamo B and the motor C is mounted an electromagnetic or other clutch M², operated by the current supplied by the dynamo B. This latter acts as a source of current in the manner hereinafter explained and at the same time as a fly-wheel for the engine A, which consequently needs no other fly-wheel for rendering its movement uniform. When the engine A is stopped, the clutch M² is uncoupled, and consequently said engine A is easily started, since the starting is effected without load. When starting has been effected, the dynamo will supply current for the clutch M², (if said clutch is an electromagnetic one,) which may be coupled. The propeller will then rotate at the same velocity as the engine A. In these conditions the engine A acts directly upon the propeller-shaft E. The dynamo B and the motor C rotate and act as a fly-wheel for the engine A; but they give no current, (except for the clutch M², if this is an electromagnetic one,) so that the transmission between the engine A and the propeller-shaft takes place without loss of energy. If desired, however, the dynamo or the motor may supply the current for the lighting of the vessel and for operating the cranes, pumps, and other appliances or machines installed upon ships and adapted to be electrically operated.

In order to reduce the speed of the propeller-shaft or reverse the direction of its rotation in regulating the number of revolutions from "0" to the normal number, (the engine A rotating invariably in the same direction and at the normal speed,) the clutch M² is uncoupled, and the propeller-shaft E is rotated by means of the current supplied by the dynamo B to the motor C. Then by the ordinary known means for regulating electro-motors all desirable changes may be speedily and exactly made either in the direction of rotation or in the velocity of the propeller-shaft. In these conditions the transmission between the motor A and the propeller-shaft E experiences the losses in the dynamo B and the motor C; but as these machines only act as transmission parts during maneuvers which are of very short duration as compared with the normal running the above arrangement may be said to effect practically the transmission between the engine and the propeller-shaft without appreciable loss of

energy. As during these operations only the velocity or the direction of rotation of the propeller, of its shaft, and of the armature of the motor is changed and as, on the other hand, the inertia of these parts is only a small fraction of the inertia of the whole of the motor mechanism in movement, it follows that the operations required during maneuvering may be effected very rapidly. This rapidity 10 may be still further considerably augmented by causing the motor to act as an electric brake for stopping the propeller-shaft.

If the clutch M^2 is an electromagnetic one, all the operations to be effected on the motor mechanism of the vessel during maneuvering, with the exception of the starting and stopping of the engines A, may be produced from any desired point of the vessel (from the upper deck, for example) without even notifying 15 the engineers in charge of the engines, who have only to attend to the regularity of the running of the engine at a constant speed and always in the same direction.

A similar arrangement may be employed 20 if two or more engines A act upon the propeller-shaft, Fig. 2. In this case, in addition to the advantages of the arrangement already described, there is that of not having to stop the vessel if one of the engines should be 25 rendered inoperative.

If the engine A' is to be repaired, it is only necessary to unclutch the coupling M' . If it is the engine A which is inoperative, the couplings M^2 M^3 are unclutched and the 30 transmission between the engine A' and the propeller-shaft E is effected by the dynamo B operating the motor C. In both cases the engine, which is inoperative, is completely stopped in such a manner that repairs may be 35 effected very easily and rapidly. In this arrangement M' M^2 M^3 are preferably electromagnetic clutches, and M^4 is an ordinary coupling-box.

In the above-described arrangements P' P^2 40 P^3 P^4 are suitable bearings.

Obviously in both cases the electromagnetic clutches may be replaced by mechanical clutches operated by hand, by water, compressed air, or any other means adapted 45 to speedily effect the coupling and uncoupling.

The above-described arrangement is evidently applicable indifferently in the case of screw-propellers or of wheel-propellers, with 50 this condition only, in the latter case, that the normal speed of the engine can be the same as that of the wheel-shaft.

What I claim is—

1. In a system for propelling vessels by aid of a non-reversible driving-engine, in combination: a non-reversible driving-engine, a dynamo mounted on the shaft of said engine, a propeller-shaft in line with the shaft of the driving-engine, an electric motor on said propeller-shaft, said electric motor being adapted to rotate in both directions and at a variable speed by the current of the dynamo, a suitable clutch adapted to connect the shaft of the driving-engine directly with the propeller-shaft when, maneuvers being completed, the propeller-shaft is to be rotated in the same direction and at the same speed as the driving-engine, the whole operating, substantially as described and for the purpose of dispensing with the use on shipboard of a secondary source of motive power for maneuvering and of avoiding the losses of motive power which would occur when running normally if the driving-engine would drive the propeller-shaft by aid of a transmitting-gear instead of directly as described. 60 70 75 80

2. In a system for propelling vessels by aid of non-reversible driving-engines in combination, two non-reversible driving-engines running in the same directions and at the same speed, a single driving-shaft common to the two driving-engines, a propeller-shaft in line with said shaft, a dynamo mounted on the common driving-shaft, suitable clutches on said driving-shaft between the dynamo and 90 each of the driving-engines, an electric motor mounted on the propeller-shaft and adapted to be rotated in both directions at variable speed by the current of the dynamo and a suitable clutch adapted to connect the shaft 95 of the driving-engines directly with the propeller-shaft when maneuvers being completed, the propeller-shaft may be rotated in the same direction and at the same speed as the driving-engines, the whole operating substantially as described and for the purpose of dispensing with the use on board of ship, of a secondary source of motive power for maneuvering and of avoiding the losses of motive power which would occur when running 100 105 normally if the driving-engines would drive the propeller-shaft by aid of a transmission-gear instead of directly as described.

In witness whereof I have hereunto set my hand in presence of two witnesses.

CESIDIO DEL PROPOSTO.
